UNITED STATES PATENT OFFICE

ALFRED FRANK, OF STUTTGART, GERMANY

IRON-FRAME WALL FOR BUILDINGS AND THE LIKE

Application filed February 28, 1928, Serial No. 257,740, and in Germany March 5, 1927.

The iron panel-work walls, known hitherto, are composed of sleepers, nogging-pieces and chases, by using such elements of the usual I or U-shapes, corresponding however 5 in their height to the width of the wall to be erected. This method of construction has several disadvantages. The wall-panels separated by vertical and horizontal wall bars, will be, after the erecting of the panel- 10 framework, lined flushly inside and outside with stone or beton, and the panel surfaces on either side and beyond the wall bars are plastered over on the places where the flanged sides of the profiles lie free, by means of a 15 plaster-bearer. The wall-bars, having the whole wall width, and the flanges being exposed throughout their width, the construction is not absolutely fire-proof.

A further disadvantage resides in the fact 20 that the heaving-strength of the lining or betoning is not taken advantage of for it serves only as filling for the panels without helping to bear any of the strains or stresses to which the wall may be subjected.

25 In consequence of the heat-conducting property of iron, damp places will be formed by moisture exuding along the flanges of the profiles, even when well plastered over. Finally the bars or scaffolding-poles, necessary 30 for finishing up the wall with nogging-pieces, are disadvantageous on account of the impracticability of fastening them to the wall when finishing it up.

35 All these disadvantages are overcome in carrying out the method of the present invention.

In the accompanying drawing two modifications of the invention are shown.

40 Figs. 1 and 2 are two vertical sections, Fig. 3 is a horizontal section through a larger part of the wall and

Fig. 4 is also a horizontal section on an enlarged scale through a part of the double-bars.

45 The invention contemplates the use of pairs of girders *a*, which are of dovetail-channel-cross section, and which stand with their inner surfaces *b* at any distance from each other. Their open sides therefore lie on the outside, 50 wherefore their iron-width lies outside, which

increases considerably its fire-proof qualities. The double-girders *a* pass from the sleeper to the chief moulding; and between the inner surfaces *b* of the double-girders *a* pass the chases *c*, the nogging-pieces, the beams or the 55 like, by which they also are joined together with U-shaped pieces *d* and the like.

The panels formed by the double-girders *a* and the horizontal wall-bars *c*, as shown in Figs. 3 and 4, are closely filled up with beton 60 *e* or the like, to the out face of the double-girders, in which the horizontal bars *c* are embedded and isolated on all sides, and the vertical girders on three sides by the filling 65 mass *e*.

The weight itself of the filling mass *e* capable of bearing after hardening, is transferred, without burdening the framework *a*, 70 *c* on the base walls passing by the two horizontal bars *c*, lying on both sides between the double girders. Thus the framework itself has only to bear the ceiling and roof-weights. The filling-mass *e* of the framework forms in 75 all directions, that is from the base-wall to the chief moulding, as well as between the double-girders *a*, a single vertical plate, capable of bearing and at the same time stiffening while in the hitherto building-method there were in this place only single and separated panels, 80 not able to bear by themselves. Bolsters *f* and scaffolds are fastened directly to the wall-bars *a*, as shown in Figs. 3 and 4, by bolts *g* whose heads are slidable in the dovetails of the girders *a*.

85 The outer and inner wall plaster *h* enters directly in the dovetail of the double-girders *a*, whereby a special fastening or a plaster-holder is never necessary.

As the posts consist of two girders *a* separated from each other, an exuding of moisture therethrough is excluded.

In the form of invention represented in Fig. 1 there is to be between the girders *a*, an edge-way placed wood *e*, while Fig. 2 90 shows in its place an I iron. While with the form of the invention shown in Fig. 1, on account of the total embedding of the edge-way placed wood *a* a rather great security 95 against fire is attained; this is consider- 100

ably increased by employing the embedded iron according to Fig. 2.

It is advantageous to use light-beton as filler, but the use of gravel-beton, on account of its great capacity of bearing, is of special advantage too, inasmuch as self-bearing walls arise, as with iron-beton, with all their advantageous qualities only with the difference that according to the present invention the armature-irons are at the same time themselves bearers for the wall-mouldings in betoning.

Claims:

1. An iron frame wall for buildings and the like comprising a plurality of pairs of spaced beams; a plurality of intermediate beams arranged transverse to and between the spaced beams and secured to the spaced beams; and a filling mass in and between the beams and forming a plane and flush with the outer limits of the spaced beams.

2. An iron frame wall for buildings and the like comprising a plurality of pairs of spaced beams, each pair arranged upright and suitably spaced; a plurality of spacing members secured between the beams; a plurality of intermediate beams arranged horizontally and transverse to and between the spaced beams on the spacing members; and a filling mass in and between the beams and forming a plane with and flush with the outer limits of the spaced beams.

3. An iron frame wall for buildings and the like comprising a plurality of pairs of spaced beams, each pair arranged upright and suitably spaced; a plurality of spacing members secured between the beams; a plurality of intermediate beams arranged horizontally and transverse to and between the spaced beams on the spacing members; and a filling mass in and between the beams and forming a plane with and flush with the outer limits of the spaced beams, said spaced beams having a dovetail-channel cross section adapted to act as a retainer for the filling mass and for an outer surface on the plane of the filling mass.

4. An iron frame wall for buildings and the like comprising a plurality of pairs of spaced metal beams, each pair arranged upright and suitably spaced; a plurality of spacing members secured between the beams; a plurality of intermediate beams arranged horizontally and transverse to and between the spaced beams, said intermediate beams being secured to the spaced beams; and a filling mass in and between the beams and forming a plane with and flush with the outer limits of the spaced beams, said spaced beams having a dovetail-channel cross section adapted to act as a retainer for the filling mass and for an outer surface on the plane of the filling mass.

5. An iron frame wall for buildings and the like comprising a plurality of pairs of

spaced metal beams, each pair arranged upright and suitably spaced; a plurality of intermediate beams arranged horizontally and transverse to and between the spaced beams, said intermediate beams being secured to the spaced beams; and a filling mass in and between the beams and forming a plane with and flush with the outer limits of the spaced beams, said spaced beams having a dovetail-channel cross section adapted to act as a retainer for the filling mass and for an outer surface on the plane of the filling mass.

In testimony whereof I affix my signature.

ALFRED FRANK.
